UNITED STATES PATENT OFFICE

2,431,837

SPICE WHEEL

Harry F. Spotts and Marian J. Spotts,
Anaheim, Calif.

Application March 12, 1946, Serial No. 653,904

5 Claims. (Cl. 211—74)

1

This invention relates to a spice wheel or a device on which a plurality of spice containers containing different spices may be mounted so that they may be rotated on the support that supports them to facilitate selection and removal of the container containing a desired spice.

An object of the invention is to provide a simple, economical and durable device adapted to be mounted on the underside of a cupboard shelf or the like and which has a rotatable support on which the spice containers are adapted to be mounted and to provide means for retaining the spice containers on the support as it revolves but which permits of the extraction and removal of a selected spice container.

With the foregoing and other objects in view, which will be made manifest in the following detailed description and specifically pointed out in the appended claims, reference is had to the accompanying drawings for an illustrative embodiment of the invention, wherein:

Figure 1 is a perspective view of a portion of a cupboard shelf illustrating the spice wheel embodying the present invention as having been mounted thereon;

Fig. 2 is a diametrical section through the spice wheel; and

Fig. 3 is a horizontal section taken substantially upon the line 3—3 upon Fig. 2.

Referring to the accompanying drawings wherein similar reference characters designate similar parts throughout, the improved spice wheel consists of a top 10 which may be formed of sheet metal or other suitable material and which has formed therein apertures 11 adapted to receive screws 12 or other fastening devices by which it may be attached to the underside of a support such as a cupboard shelf S. The central portion of the top 10 is depressed as indicated at 13 and a bolt 14 extends downwardly therethrough and through a central depressed portion 15 of a bottom or support 16. The bottom or support is of substantially the same diameter as the top 10 and has secured thereto a cylindrical hub 17. The hub 17 may be attached to the bottom or support 16 in any suitable manner such as by brackets 18 that may be spot-welded or otherwise permanently attached to the hub and to the bottom. Near the top of the hub there is preferably a spider 19 which braces the upper portion of the hub and through which the bolt 14 extends. By means of this construction although the top 10 is rigidly and permanently fastened to the shelf S the bottom 16 and the hub 17 are freely rotatable relatively thereto. The top and bot-

2

tom have opposed flanges, the flange of the top being indicated at 20 and the flange at the bottom being indicated at 21. These flanges are spaced from the hub 17 a distance slightly in excess of the thickness of a conventional spice can or like containers. The top and bottom flanges 20 and 21 are spaced from each other a distance slightly less than the height of a conventional spice can or like container. At one side of the flange 20 there is formed a cut-out 22 which in width is slightly greater than the width of a conventional spice can. The top of this cut-out is so spaced from the flange 21 as to permit of a single spice can to be tipped outwardly there-through in removing it from the spice wheel.

By means of the above described construction it will be appreciated that a plurality of spice cans or like containers may be inserted between the top and bottom by tipping them consecutively through the cut-out 22. These cans may be arranged in side by side relationship around the hub 17 and are supported on the bottom 16. When it is desired to select a particular spice the bottom 16 may be manually rotated to carry the various spice cans consecutively across the obverse side of the wheel. During the rotation even though the spice cans may be subjected to centrifugal force tending to throw them outwardly they are effectively retained on the bottom 16 by the flanges 20 and 21 which, as above noted, are spaced from each other a distance less than the height of the can. When the desired spice has been located on the support its container is arranged opposite the opening 22 and it can be withdrawn through this opening by tilting it outwardly. It may be restored to the wheel by inserting it through the opening in a reverse manner.

It will be appreciated that the above described construction enables a large number of different spices to be conveniently kept in a cupboard but in such a manner that on mere rotation of the bottom the various containers may be consecutively brought to view for purposes of selection.

While the invention has been primarily designed for mounting and storing spice containers it is equally applicable to other articles, a plurality of different kinds of which are to be conveniently stored in such a manner that they may be readily selected.

Various changes may be made in the details of construction without departing from the spirit and scope of the invention as defined by the appended claims.

We claim:

1. A device of the class described comprising an annular lower support, a top to which the lower support is rotatably secured, said support and top having opposed flanges cooperating to retain containers of spices or the like adapted to be placed on the support as the support rotates relative to the top, and a cut-out in the flange of the top permitting a selected one of the containers to be tipped therethrough in removing it from the support after having been carried by the support into registration therewith.

2. A device of the class described comprising a top adapted to be secured to the underside of a shelf or the like, a support suspended for rotation from the top, a hub secured to the support and rotatable therewith, said top and support having opposed marginal flanges spaced from the hub a distance slightly in excess of the width of a spice can or the like, and spaced from each other a distance slightly smaller than the height of a spice can and adapted to confine spice cans on the support as the support rotates, and a cut-out in the flange of the top through which a spice can may be tipped in removing it from the support.

3. A device of the class described comprising a top adapted to be secured to the underside of a shelf or the like, a support suspended for rotation from the top, a hub secured to the support and rotatable therewith, said top and support having opposed marginal flanges spaced from the hub a distance slightly in excess of the width of a spice can or the like and spaced from each other a distance slightly smaller than the height of a spice can and adapted to confine spice cans on the support as the support rotates, and a cut-out in one of the flanges through which the spice can may be tipped in removing it from the support.

4. A device of the class described comprising a circular top adapted to be secured to the underside of a shelf or the like, a circular support suspended at its center from the top and rotatable relative thereto, a hub secured to the support, a spider adjacent the top of the hub, said hub and spider being rotatable with the support, said top and support having opposed marginal flanges spaced outwardly from the hub, and a cut-out in the flange on the top enabling a container adapted to be supported on the support to be tipped therethrough.

5. A device of the class described comprising a top adapted to be secured to the under side of a shelf or the like, a continuous annular support rotatably suspended from the top on which a plurality of spice cans or the like are adapted to be supported, the top and support having opposed annular flanges adapted to mutually cooperate to retain the cans on the support as the support is rotated, and a cut-out in the flange on the top with which any selected can on the support may be brought into registration as the support is rotated and through which the selected can may be tipped in withdrawing it from the support.
